SIEGMUND LOEWE, OF BERLIN, FRIEDENAU, GERMANY, ASSIGNOR TO RADIO CORPORATION OF AMERICA, A CORPORATION OF DELAWARE

AMPLIFIER TUBE

Application filed October 20, 1926, Serial No. 142,818, and in Germany October 21, 1925.

This invention relates to a vacuum tube and more particularly to a single vacuum tube for producing multi-stage amplification of low frequency currents.

The use of a high resistance in the plate circuit of an amplifier to produce a very high and efficient potential amplification is well known. However, the value of the resistance used is limited by stray capacities, such as exist between the leads and internal elements of the tubes, where there is more than one stage of amplification, and in turn, this limits the potential amplification.

It is an object of this invention to reduce such stray capacities to a minimum. This, as will be pointed out later in greater detail, is accomplished by placing the elements of the various stages within a single vacuous space, thereby reducing the length of the leads.

Another object of this invention is to build an inexpensive multi-stage low frequency amplifier.

A further object is to build a multi-stage amplification unit, that is compact, and can be used effectively in various circuits to simplify them.

Other objects as well as advantages will appear as the description of the invention proceeds.

In the accompanying drawing I have shown an embodiment of my invention, namely, a two stage resistance coupled amplifier within a single tube. The glass bulb of the tube is indicated at 12.

It is to be understood of course that amplification systems other than those shown may be used.

In the drawing 1 designates a compressed foot or base through which run the leads to the amplification systems. 7 designates the elements of the first stage of amplification and 8, those of the second. As is clearly shown the filaments of the two stages are connected in series, the external leads 2 and 3 providing a means whereby a heating current may be supplied to them. 4 is the lead to the first grid, 5 to the first plate and 6 to the second plate. 9 indicates a high resistance used in the plate circuit of the first stage for the purpose of producing high potential am-

plification. 11 is the well known grid condenser which as shown is preferably hermetically enclosed, or, if desired, may be confined within an exhausted tube. Resistance 10 is the well known grid leak resistance. Resistances 9 and 10 should be of the type that will not undergo a change in value due to heating such as the heating of the tube when the vacuum within it is being produced. Resistances of this kind may be obtained by vaporizing carbon or metal upon a glass or quartz carrier.

The resistances 9 and 10 are not disposed in the plane of the two systems 7 and 8 as illustrated, but one resistance, for example, 9 is placed behind the plane of the drawing and the other in front of that plane. This is done in order to reduce capacity effects to a minimum and also to reduce the total space required by the apparatus.

Frequently in order to insure an extreme vacuum, magnesium, or the like, is vaporized within the tube. Care should be taken to protect resistances 9 and 10, condenser 11 and the base from the deposition of such metallic vapors. Otherwise inadmissible variations in resistance, or rather, conductive bypasses or shunts may be produced which will greatly decrease the efficiency of the tube.

The advantages of my arrangement are at once apparent. By placing the elements of each amplification system as well as the coupling means within a single tube the need for separate tubes as well as complicated connections is dispensed with. By quantity production of these tubes a unitary multi-stage amplification system can be produced which is less expensive than the cost of several single stage units, which would be required to produce the same amplification.

By mounting the elements and coupling means on a single base this amplification device becomes easy to handle. It is clear that the use of such a device in various circuits will simplify them and avoid the necessity of intricate wiring.

Having described my invention what I claim is:

In a multi-stage vacuum tube, a base; a plurality of amplifier units, each comprising a

control electrode, a cathode and an anode mounted in one plane on said base; a coupling condenser connecting the anode of one of said units with the grid of another; a resistance connected to one side of said condenser; and another resistance connected to the other side of said condenser; said resistances being mounted in a plane traversing the plane of said units.
